CLAIM

The ornamental design for a substrate for an electronic circuit, as shown and described.

DESCRIPTION

The patent or application file contains at least one drawing executed in color. Copies of this patent or patent application with color drawing(s) will be provided by the Office upon request and payment of the necessary fee.

FIG. 1 is a perspective view of a substrate for an electronic circuit showing our new design;

FIG. 2 is a rear perspective view thereof;

FIG. 3 is a front elevational view thereof;

FIG. 4 is a rear elevational view thereof;

FIG. 5 is a right side elevational view, a left side elevational view being a mirror image thereof;

FIG. 6 is a top plan view thereof; and,

FIG. 7 is a bottom plan view thereof.

The black circles shown in FIGS. 2 and 4 are flat on the surface of the electronic circuit.

The even dashed broken lines shown in the drawings represent portions of the substrate for an electronic circuit that form no part of the claimed design. The dashed-dot-dashed broken lines define the boundaries of the claimed design.
